[57] ABSTRACT

A lid supporting device for engagement with the upper portion of a container wall comprising a single piece of heavy gauge wire formed to have a wall-spanning back portion, a first leg, a second leg, and a sleeve of resilient non-abrasive material surrounding a major portion of the back portion. The first leg comprises a generally linear length of wire and a smoothly curved tail of wire at its lower end.

2 Claims, 4 Drawing Figures

FIG 1**FIG 2****FIG 3****FIG 4**

1
LID SUPPORT

This invention relates to a device for supporting the lid of a covered container in a partially open position.

It is a principal object of the invention to provide a device of the type described which is easier to manufacture than previous such devices and is suitable for use with containers having a variety of configurations of the lid rim.

To achieve these objects the invention contemplates a lid support device comprising a back portion and first and second leg portions, all formed from a single piece of heavy gauge wire, and a resilient non-abrasive sleeve surrounding at least a major portion of the back portion. The first leg includes a generally linear portion and a curved tail portion at the lower end thereof. The second leg comprises three generally linear portions joined in a form to approximate a triangle. In preferred embodiments, the sleeve also surrounds at least part of the linear portion of the first leg; the back portion is itself generally linear; and the plane of the triangle defined by the three linear portions of the second leg is inclined at an acute angle to the axis of the back portion.

Other objects, features, and advantages will appear from the following description of a preferred embodiment, taken together with the attached drawings thereof.

In the drawings:

FIG. 1 is a perspective view of a lid supporting device according to the invention;

FIG. 2 is a plan view of the device of FIG. 1;

FIG. 3 is an end view of the device of FIG. 1; and

FIG. 4 is a side view of the device of FIG. 1 in use.

Referring to the drawings, a lid supporting device 10 is made from a single piece of heavy gauge wire (e.g., No. 11 wire). In the preferred form shown in the drawings approximately 11 inches of such wire is required.

The device 10 includes a generally linear back portion 12, a first leg 14, and a second leg 16. The first leg 14 includes a generally linear length of wire 18 and a smoothly curving tail 20 of wire at the lower end of length 18. In its preferred form, the tail 20 is curved sharply enough that the extreme end 22 of the wire will be substantially adjacent the vertical length 18. Furthermore, the tail 20 bends toward the second leg 16 so as to provide a convenient container wall-engaging surface which cooperates with a similar surface of the second leg to grasp the container wall.

The second leg 16 includes generally linear lengths of wire 24, 26, and 28. These lengths are arranged in an approximately triangular configuration with the plane of that triangle inclined at an acute angle to the axis of back portion 12 (best seen in FIG. 4). With this configuration, the length 26 (the base of the triangle) is closest to the first leg 14 and thus acts as the wall-engaging

portion of second leg 16. An extension 30 of length 28 is sharply bent around the upper portion of length 24 to provide for a stronger and more stable configuration of second leg 16.

5 Sleeve 32 is provided which surrounds the wire of back portion 12 as well as a large portion of the vertical length 18 of wire in the first leg 14. The sleeve is preferably plastic tubing but may be any non-abrasive material. For a lid supporting device constructed from an 11 10 inch length of No. 11 wire, sleeve 32 may be a 2 1/2 inch length of plastic tubing having a one-eighth inch inner diameter.

As best seen in FIG. 4, in operation the device is placed over a wall 34 of a container with the wall being 15 grasped between tail portion 20 of first leg 14 and length 26 of leg 16. With the first leg 14 disposed on the inside of the container, the lid 36 of the container will rest upon the sleeve 32 no matter what the configuration of the lid in its peripheral region (i.e., even if there 20 are recesses or protrusions designed to engage with mating structures on the upper edge of the container wall).

The triangular form of second leg 16 provides a wide base (i.e., length 26 of wire) over which force is applied 25 when the wall 34 is grasped. This construction, therefore, provides a substantial measure of stability to the device 10 which would be lacking if both legs applied pressure to the wall 34 over a very limited area (as is the case with the first leg 14). It will be apparent, however, that the length of second leg portion 26 may be varied in relation to the length of portions 24 and 28 while retaining this stability advantage.

Other embodiments of the invention will occur to those skilled in the art and are within the following 30 claims.

What is claimed is:

1. A lid supporting device for supporting a container lid in a slightly open position and engageable with the upper portion of the container wall, the device comprising a single piece of wire, said wire formed to have a linear wall-spanning back portion extending substantially perpendicular to said wall upon engagement of said device with said upper portion, a first leg integral with said back portion comprising a generally linear length of wire and a tail of wire at the lower end thereof smoothly curved in the plane of said back portion, a second leg integral with said back portion, and a sleeve of resilient non-abrasive material surrounding a major portion of said back portion and said linear length of said first leg.

40 2. The device of claim 1 wherein said second leg comprises three generally linear lengths of said wire in approximately triangular form, the lowest of said three lengths lying in a plane generally perpendicular to the 45 plane of said back portion.
